AUTOMATIC LOCK SLIDER

Alfred E. Carlile, Great Neck, N. Y., assignor to
Talon, Inc., a corporation of Pennsylvania

Application August 15, 1944, Serial No. 549,508

8 Claims. (Cl. 24—205.14)

1

This invention relates to slide fasteners and, particularly, to an improved automatic lock slider therefor having a locking means especially adapted for use with non-metallic sliders.

It is a well-known fact that sliders made from non-metallic materials, for example, plastic or thermoplastic material such as cellulose acetate or cellulose nitrate, are considerably weaker in their construction than sliders made from metal, and consequently, many factors prevent the use of designs known for automatic locking metallic sliders. For instance, the plastic material from which non-metallic sliders are made is usually relatively soft compared with metal and obviously, is subject to excessive wear at bearing surfaces, especially should the locking member be pivotally attached to the plastic slider body. Also, the locking element and parts thereof, due to the characteristics of the material of a plastic slider body, can be neither conveniently nor successfully attached thereto as they can in the case of a metallic slider body.

Accordingly, it is the general object of the present invention to provide a non-metallic slider having an automatic locking means which is simple and inexpensive and which can be easily and conveniently applied to the slider body and, at the same time, a locking means which is efficient and effective in its use and one which will not subject the slider body to wear.

It is another object of the invention to provide an improved locking means which can be conveniently incorporated with non-metallic slider bodies of the non-locking type as they are presently being manufactured without departing materially from the present design or manufacture thereof, thereby eliminating the necessity of providing any material changes in existing dies or molds in the manufacture of automatic lock sliders in accordance with the present invention.

It is a further object of this invention to provide an improved locking element for non-metallic sliders in the form of a clip-like member which can be assembled on the slider body merely by positioning the locking element thereon and forcing the same into engagement with the slider by a snapping action, thereby eliminating the need for any expensive assembling tools or other equipment.

It is still another object of the present invention to provide an improved automatic non-metallic lock slider which consists of a minimum number of parts and one which is strong and rugged in its construction, having a locking ele-

2

ment which will not crush or become distorted when a normal pressure is applied to the top of the slider body.

Various other objects and advantages of this invention will be more apparent in the course of the following specification, and will be particularly pointed out in the appended claims.

In the accompanying drawings, there is shown for the purpose of illustration, one embodiment 10 which my invention may assume in practice.

In these drawings:

Fig. 1 is a plan view of a slide fastener with the improved automatic lock slider of my invention incorporated therewith;

15 Fig. 2 is an enlarged sectional view taken on line 2—2 of Fig. 1.

Fig. 3 is a bottom end view of the same;

Fig. 4 is a perspective view of the locking member; and

20 Fig. 5 is a sectional view taken on line 5—5 of Fig. 2.

Referring more particularly to the drawings, there is shown in Fig. 1 a conventional type of slide fastener comprising cooperating rows of spaced interlocking fastener elements 2 attached to the opposed beaded edges of tapes or stringers 3. There is arranged on the rows of fastener elements a slider, generally designated at 4, for longitudinal movement therealong in opposite 30 directions for opening and closing the fastener in a manner well-known to those skilled in the art.

It is preferable that the type of slider used with the present invention be of the type disclosed 35 in the patent to N. J. Poux, No. 2,274,161, dated February 24, 1942, which comprises a one-piece integral molded hollow slider body having a top or upper wing 5 and a bottom or lower wing 6, which are connected by an integral neck portion

40 7. There is carried by the wing portions, inwardly extending flange portions 8 for guiding the fastener elements through the Y-shaped channel of the slider body. On the outer side of the top or upper wing 5, there is arranged integral with

45 the slider body, a longitudinally extending and centrally disposed lug or loop portion 9, having an arcuated upper surface 10. There is arranged through the lug or loop portion 9, an elongated transversely extending aperture 13 by means of

50 which the pull tab or member is adapted to be attached to the slider body. In the upper end of the neck portion 7, centrally of the slider body, there is arranged a recess 12, which extends a substantial distance into the neck portion, as shown in Fig. 2 of the drawings.

According to the present invention, there is provided a locking element 14, which is made preferably from an elongated relatively thin strip of inherently resilient metallic material. This locking element is preferably arcuated so as to conform to the upper arcuated surface 10, of the lug or loop 9, on which it is adapted to be disposed in one position, in a manner hereinafter to be described.

One end of the locking element is preferably reduced and tapered so as to provide a tongue or tab portion 15 on the end thereof, having a width slightly less than the width of the recess 12 in the neck portion 7 of the slider body. On the opposite end of the locking element, preferably to one side thereof, there is arranged a locking pin or projection 16, which is adapted to cooperate with the fastener elements to lock the slider against movement, in a manner later to be described. Intermediate the length of the locking element 14 and substantially centrally thereof, there is struck up from the material thereof, a pair of spaced-apart inwardly extending tab portions 17 and 18, thereby leaving a rectangular opening 19 substantially in the center of the locking element. The extreme ends of each of the tab portions 17 and 18 are preferably bent or turned outwardly from each other so as to provide arcuated portions 20 and 21, respectively, on the extreme ends thereof.

The upper surface of the lug or loop portion 9 of the slider body is preferably drilled at spaced-apart points intermediate the width thereof directly above the aperture 13 therethrough, so as to provide a pair of spaced-apart holes 22 and 23. The holes 22 and 23 are positioned so that they communicate with the transverse aperture 13 in the lug adjacent each end thereof. Between the holes 22 and 23, there is arranged on the upper surface of the lug or loop 9, preferably a rectangular-shaped raised portion 24 so as to provide a rectangular pad-like key portion which extends above the remaining portions of the lug or loop, for a purpose to be described.

The locking element of the present invention is assembled on the slider body in the following manner. It will be understood that the locking element is designed in the form of a clip-like member, and is inherently resilient, so that it can be sprung into position on the slider body and held thereon solely due to its resilient characteristic. The locking element is positioned on top of the lug or loop 9 and is forced downwardly upon the arcuated surface of the lug or loop. In forcing the locking element to such position, it will be seen that the tab portions 17 and 18 will be moved into the holes 22 and 23, respectively, in the lug portion 9, and that when the locking element is moved to superposed position against the upper surface of the lug or loop, the inwardly extending tab or tongue portion 15 on one end of the locking element, will be moved and sprung into the recess 12 in the neck portion 7. It will be seen that the locking element, while it is being forced into position on the lug, is sprung and that when it is finally in position on the lug, that it is held on the slider body, due primarily to the resiliency of the locking element. In other words, the locking element, after being sprung, is held in position on the lug of the slider body by means of the tongue or tab portion 15 disposed in the recess 12 and the tab portions 17 and 18, which are disposed in the holes 22 and 23, respectively, in the lug 9.

After the locking element has been assembled or snapped on the slider, as above described, it will be seen that the outer ends of the tab portions 17 and 18, extend into the transverse aperture 13, with the arcuated end portion 20 of the tab portion 17 being disposed at the upper end of the elongated aperture 13 and with the arcuated end portion 21 of the tab portion 18 being disposed at the lower end of the aperture. The pad-like key portion 24 of the lug 9 is disposed in the rectangular recess 19 of the locking element so as to aid in positioning and maintaining the locking element in proper position on the lug. The lower or front end of the upper wing 5 is preferably recessed as at 25, so that the front portion of the locking element will be disposed therein after the locking element has been forced into position on the slider body. The locking prong 16 after assembly, extends below the top wing 15 into the lower end of the Y-shaped channel of the slider body.

After the locking element has been mounted on the slider body, as above described, a pull member 26 is attached thereto with the pivotal or trunnion portion 27 thereof disposed movably in the transverse aperture 13 of the lug or loop 9 in a well-known manner.

When it is desired to move the slider along the fastener elements in a direction to close the fastener, it will be seen that the pivotal portion 27 of the pull strikes the arcuated portion 20 of the tab portion 17 at the upper end of the aperture 13, thereby lifting the locking element together with the locking prong carried thereby, out of the slider channel and out of engagement with the fastener elements therein. After the pull has been released, the locking element again assumes its normal position against the arcuated surface 10 of the lug 9 upon which it normally rests, with the locking prong 16 disposed between the fastener elements, thereby automatically locking the slider against unintentional movement. When the slider is moved in the direction to open the fastener, it will be seen that the pivotal portion 27 of the pull strikes the arcuated portion 21 of the tab portion 18 at the lower end of the aperture 13, thereby again moving the locking element together with the locking projection 16, carried thereby, out of engagement with the fastener elements.

As a result of my invention, it will be seen that there is provided an automatic lock slider consisting of a minimum number of parts, namely, three, having a locking element which can be easily and quickly assembled on the slider body without the aid of tools or auxiliary fastening means. It will be seen also that the locking element can be conveniently fabricated from standard metallic stock and that the slider body can be conveniently molded either from metallic or non-metallic materials.

While I have shown and described one embodiment which my invention may assume in practice, it will be understood that this embodiment is merely for the purpose of illustration and description and that various other forms may be devised within the scope of my invention as defined in the appended claims.

What I claim as my invention is:

1. In a slider for slide fasteners of the class described having a body member with an interior channel through which the fastener elements pass for engaging and disengaging the same, and a pull member, a locking device comprising a longitudinally extending lug positioned on the outer side

of said body member, an inherently resilient longitudinally extending locking member mounted on said lug, said locking member conforming substantially to the outer surface of said lug and being disposed thereon in superposed relation so as to encircle the same substantially throughout the length thereof, said locking member having means carried thereby at one end thereof engaging the slider body so that said end is substantially immovable relative thereto and having a locking projection on its opposite free yieldable end adapted normally to be urged, due to the inherent resiliency thereof, into engagement with the fastener elements to lock the slider, said pull member connected to said lug for actuating said slider, said locking member having means carried thereby intermediate the length thereof which cooperates with said pull whereby said locking member is moved out of engagement with the fastener elements when the pull is manipulated to move the slider in either direction along the fastener elements.

2. In a slider for slide fasteners of the class described having a body member with an interior channel through which the fastener elements pass for engaging and disengaging the same, and a pull member, a locking device comprising a longitudinally extending lug positioned on the outer side of said body member, an inherently resilient longitudinally extending locking member mounted on said lug in superimposed relation, said locking member conforming substantially to the outer surface of said lug so that it rests thereon and encircles the same substantially throughout the length thereof, said locking member having means carried thereby at one end thereof engaging said slider body and having a locking projection on its opposite free end adapted in one position to engage the fastener elements to lock the slider, said lug having a transversely extending aperture arranged therethrough intermediate the length thereof, said pull member having the pivotal portion thereof disposed in said aperture, and means carried by said locking member which extends into said aperture and with which the pivotal portion of said pull cooperates whereby said locking member is moved out of engagement with the fastener elements when the pull is manipulated to move the slider in either direction along the fastener elements.

3. In a slider for slide fasteners of the class described having a body member with an interior channel through which the fastener elements pass for engaging and disengaging the same, and a pull member, a locking device comprising a longitudinally extending lug arranged on the outer side of said slider body, a spring locking member comprising a relatively thin piece of resilient material mounted on said lug in superimposed relation, said locking member conforming substantially to the outer surface of said lug so that it rests thereon and encircles the same substantially throughout the length thereof, said locking member having means carried thereby at one end thereof engaging said slider body and having a locking projection on its opposite free end adapted in one position to engage the fastener elements to lock the slider, said lug having an elongated transverse aperture arranged therethrough intermediate the length thereof, said pull member having the pivotal portion thereof disposed in said aperture, said lug having at least one opening arranged in the outer surface thereof communicating with said transverse aperture, and a pair of spaced-apart inwardly projecting tab portions carried by said

locking member and extending through the opening in said lug into said transverse aperture with one positioned adjacent each end thereof and with which the pivotal portion of said pull cooperates whereby said locking member is moved out of engagement with the fastener elements when the pull is manipulated to move the slider in either direction along the fastener elements.

4. In a slider for slide fasteners of the class described having a body member with an interior channel through which the fastener elements pass for engaging and disengaging the same, and a pull member, a locking device comprising a longitudinally extending lug arranged on the outer side of said slider body, a spring locking member comprising a relatively thin piece of resilient material mounted on said lug in superimposed relation, said locking member conforming substantially to the outer surface of said lug so that it rests thereon and encircles the same substantially throughout the length thereof, said locking member having means carried thereby at one end thereof engaging said slider body and having a locking projection on its opposite free end adapted in one position to engage the fastener elements to lock the slider, said lug having an elongated transverse aperture arranged therethrough intermediate the length thereof, said pull member having the pivotal portion thereof disposed in said aperture, a pair of spaced-apart openings arranged in the outer surface of said lug with one of said openings being positioned adjacent each end of said transverse aperture and communicating therewith, and a pair of spaced-apart inwardly projecting tab portions carried by said locking member with one of the tab portions disposed in each of said openings and extending into said transverse aperture with which said tab portions the pivotal portion of said pull cooperates whereby the locking member is moved out of engagement with the fastener elements when the pull is manipulated to move the slider in either direction along the fastener.

5. In a lock slider of the class described having a channeled slider body with spaced wing portions connected at one end thereof by a neck portion and with one of said wings having a centrally and longitudinally extending arcuated lug arranged on the outer surface thereof, and a pull member, a locking device comprising a spring locking element consisting of an elongate relatively thin strip of resilient material, said element being arcuated and disposed on said arcuated lug in superposed relation, means arranged on one end of said element engaging the slider body adjacent the neck portion thereof, a locking projection arranged on the opposite free end of said locking element, said lug portion having a transverse aperture extending therethrough intermediate the length thereof, said pull member pivotally attached to said lug and extending through said aperture, and means carried by said locking element extending into said aperture with which said pull member cooperates to move the locking element to unlocked position, said locking element being constructed and arranged so that it is held in position on said lug portion primarily due to the inherent resiliency of said element.

6. In a lock slider of the class described having a channeled slider body with spaced wing portions connected at one end thereof by a neck portion and with one of said wings having a centrally and longitudinally extending arcuated

lug arranged on the outer surface thereof, and a pull member, a locking device comprising a spring locking element consisting of an elongate relatively thin strip of resilient material, said element being arcuated and disposed on said arcuated lug in superposed relation, means arranged on one end of said element engaging the slider body adjacent the neck portion thereof, a locking projection arranged on the opposite free end of said locking element, said lug portion having an elongated transverse aperture extending therethrough intermediate the length thereof, said pull member pivotally attached to said lug and extending through said aperture, and a pair of inwardly projecting spaced-apart tab portions carried by said element intermediate the length thereof and projecting through openings in the lug into said transverse aperture and with which said pull member cooperates to move the locking element to unlocked position, said locking element and said tab portions being constructed and arranged so that said locking element is held in position on said lug portion primarily due to the inherent resiliency of said element.

7. In an automatic lock slider for slide fasteners of the class described having a channeled slider body of thermoplastic material consisting of spaced-apart wing portions connected by a neck portion, and a pull member, a locking device comprising an arcuated lug portion arranged centrally and longitudinally of the other surface of one of said wing portions, a spring locking element consisting of an elongated relatively thin strip of resilient material, said element being arcuated and disposed on said lug portion in superposed relation, a locking projection arranged on the opposite free end of said locking element, said lug portion having a transverse aperture extending therethrough intermediate the length thereof, said pull member pivotally attached to said lug portion and extending through said aperture, means carried by said locking element extending into said aperture with which said pull member cooperates to move the locking element to unlocked position, and means carried by said locking element for attaching the same to the slider whereby it can be positioned on said lug portion and sprung, due to the resiliency thereof, into engagement with said slider body.

8. In an automatic lock slider for slide fasteners of the class described having a channeled slider body of thermoplastic material consisting of spaced-apart wing portions connected by a neck portion having a recess arranged in the outer side thereof, and a pull member, a locking device comprising an arcuated lug portion arranged centrally and longitudinally of the other surface of one of said wing portions, a spring locking element consisting of an elongated relatively thin strip of resilient material, said element being arcuated and disposed on said lug portion in superposed relation, and having an inwardly projecting portion arranged on one end thereof which is disposed in the recess of said neck portion, a locking projection arranged on the opposite free end of said locking element, said lug portion having a transverse aperture extending therethrough intermediate the length thereof, said pull member attached to said lug portion by means of said aperture, and a pair of inwardly projecting spaced-apart tab portions carried by said locking element intermediate the length thereof and projecting through openings in the lug portion into said transverse aperture and with which said pull member cooperates to move the locking element to unlocked position, both said inwardly projecting portion on one end of said locking element and said tab portions carried thereby being constructed and arranged so that said element is held in position on said lug portion, due primarily to the resiliency thereof.
